ABSTRACT OF THE DISCLOSURE

Process and apparatus for preventing abrasive components causing wear in gear pumps and the like metering abrasive containing materials to a liquid stream comprising continuously feeding a liquid free of abrasive-causing components along various component pump elements, such as a drive and rotor shaft, associated metering gears and the like; provision also is made for placing the pump in a bypass conduit wherein a portion of a liquid, for example, a viscous liquid being manufactured into filaments, fibers and films, is used as a lubricating and flushing liquid.

This invention relates to a method and apparatus for supplying to a stream of viscous liquids an additive having a relatively low viscosity and having an abrasive component of poor lubricating power.

Various methods and apparatus for supplying or injecting an additive into a bypass stream of a main stream of viscous liquid flow are known and, for example, many those skilled in the art often employ such expedients for adding a low viscosity titanium dioxide suspension to a main stream of a relatively high viscosity spinning solution for the manufacture of artificial threads. Usually for this purpose the additive is preferably injected into the bypass stream between two gear type pumps. With this method and wherein gear pumps are used, the speed or rate of delivery of one gear pump is always greater than the delivery of a second of such pumps so that between the two pumps there exists a reduced pressure which is used for suction purposes and correct metering of the masses to be admixed.

It has now been found that, particularly when an abrasive component is present in the liquid to be introduced, rapid wear occurs on the gear pump through which the admixed liquid last passes. An abrasive component and/or the relatively thin carrier liquid being introduced may easily get between the side faces of the gears, the boundaries thereof, and the shaft bearings and as a result, the two liquids are not satisfactorily mixed. This wear is especially increased when the additive is of a lower viscosity than the liquid being passed and considered as the main stream.

Thus, it is the object of this invention to provide a method and apparatus for reducing or entirely avoiding wear of a gear pump used for finally metering an injected second liquid to a main liquid flow stream.

This and other objects of the present invention are achieved by preventing an abrasive component and/or other types of low viscosity liquids from entering and thus interfering with the bearings of said pump by providing a continual flow of the higher viscosity liquid (for example, the liquid being manufactured into filaments, fibers or film and entirely free of or unmixed with the lower viscosity or abrasive containing liquid) along various driven parts, such as the drive shaft and associated gears of the metering pump used for introducing the lower viscosity or abrasive containing liquid to a main stream flow.

2

Not only does the novel method and apparatus of this invention almost entirely prevent the aforementioned wear but they also give rise to certain advantages associated with avoiding the necessity of using extremely accurate sealing means previously required to prevent the abrasive component and/or low-viscosity liquid from getting to vulnerable areas within the pump. The invention also precludes the necessity of using a special and very expensive pump lubricant which tends to form impurities in the final product.

10 The highly viscous liquid stream, which serves to continually wash and lubricate the various parts of the pump, may be branched off at any point where the main stream has not been admixed with another liquid. It may be 15 branched off from the main viscous conduit, from a supply conduit to a first gear pump, or from a discharge conduit somewhere before a point where the additive is introduced. For practical reasons, however, it has been found particularly advantageous to branch off the higher 20 viscosity liquid stream between a point at which the main stream is branched off and a point where the first branch stream rejoins the main stream.

Adequate protection from wear is obtained if, according to the invention, a liquid stream is passed through a second branch conduit or side stream at a throughput of 25 about 0.5 to 10% of the total rate delivery of the pump, depending on the absolute capacity of the pump, the lubricating power of the main liquid and the additive(s), and the materials of which the pump is made. In some cases, 30 merely a 4% lubricating stream was found to give adequate results.

The final mixing result obtained by the present method and apparatus may be further influenced by the rates of flow of the liquid through the various branches of the 35 conduit system. A more favorable mixing result is obtained if the proportion of the main stream passed through the first side stream or branch conduit is relatively large, and, according to the invention, it is preferred that the method be carried out wherein the difference in the delivery rate of the first and of the second pump in the branch line is about 5 to 20%, preferably around 10% of the delivery rate of the second pump.

If in the pump to be protected from wear, there exists a liquid pressure greater than the liquid pressure at the 45 point where the second side stream joins with the main stream, then the flow of the protecting liquid stream may be maintained without making any special provisions. It has been found that this condition is difficult to realize in actual practice, however. It is therefore preferred that the second stream be branched from the main stream through a gear pump in order to permit and maintain proper flow. The gear pump can then also serve to accurately meter the protecting liquid stream.

It should be noted that in pumping a relatively high 55 viscosity spinning liquid high demands are made on the uniformity of pump outputs; therefore, components of the pumps must be accurately dimensioned and play between various parts must be very small and appreciable wear must not be allowed to occur.

60 Wear of the second gear pump in the first branch conduit is reduced even further and use can be made of an even smaller protective stream, provided a low-viscosity additive (with the abrasive component) is previously mixed with the viscous liquid in the first branch conduit 65 before flowing through the second gear pump. It is therefore preferred to have the additive mixed with the viscous liquid in the first branch conduit between the two gear pumps by means of a mechanically operated mixer. Subsequently, and especially after the branch stream has 70 rejoined the main stream, the liquid may be further passed through a mechanical mixer or alternatively, a mixing device comprising a series of stationary baffles or re-

strctors as disclosed in commonly assigned U.S. Letters Patents Nos. 3,051,452 and 3,051,453.

To enable one to effectively carry out the method according to the invention, the housing of the second gear pump in the first branch conduit should be provided with an additional feed inlet which communicates with a system of channels that feed into openings or spaces provided near the ends of the pump shafts and closely adjacent to the shaft sealing means therefor. In this way, the protecting liquid is led to a point from which it may be evenly distributed along the shaft bearings and the side faces of the pump gears. Proper liquid distribution along the side faces automatically insures proper protection of the shaft bearings. It is also preferred to use a gear pump having a gear drive shaft wherein the shaft ends are provided with helical grooves which run to near the side faces of the gears. By use of this expedient, resistance to the protecting liquid flowing therethrough is reduced. Constructing the grooves with proper directional characteristics also serves to effectively pump the liquid along the drive shaft.

Apparatus for effectively carrying out the invention comprises a main spinning liquid conduit provided with a pump, e.g. a gear pump, and, beyond the pump, a bypass branch conduit in which two gear pumps are located and separated by an inlet for the pigment suspension. In the main conduit (and at a point where no additive has been admixed with liquid from the main conduit), there is connected a second branch conduit in which an additional gear pump is located. This second branch conduit feeds into an additionally provided feed inlet of the second gear pump in the first branch conduit. The construction of this second gear pump constitutes a significant portion of the invention, as described above and as set out in more detail below.

Spinning liquids to which the materials may be added according to this invention comprise natural polymers such as viscose, acetate casein; or synthetic polymers such as polyamides, aromatic polyesters, polyphenylene oxides or acrylonitriles. Suspensions to be admixed may be pigments and/or other aids to improve the spinning process or the quality of the product, e.g., titanium dioxide.

Reference is made to the accompanying drawings and description thereof and wherein:

FIGURE 1 is a schematic representation of the apparatus according to the invention.

FIGURE 2 shows the novel bypass and fluid flow of the gear pump comprising the essential elements in detail according to this invention.

In FIGURE 1, numeral 1 refers to a main conduit for a stream of viscose. The viscose is pumped through the conduits by gear pump 2. At 3, conduit 4 branches off from main conduit 1 and runs through additional gear pumps 5 and 6. Between gear pumps 5 and 6, conduit 7 enters into the conduit, at which point there is located a closed mixer 8 which is provided with convenient stirrer means. The liquid discharged by the gear pump 6 passes through the conduit 9 and re-enters the main conduit 1 at connection 10.

At 11, before connection 10, a second conduit 12 branches off and runs through gear pump 13 to gear pump 6.

When the liquid streams through the conduits 1 and 9 have joined again at 10, the reunited main stream passes through mixer 14. Mixer 14 is of the stationary type and can be of the type disclosed in U.S. Patents No. 3,051,452 and No. 3,051,453. Through conduit 7 a stream of a pigment suspension is fed to mixer 8. This stream is mixed with the stream of viscose flowing through the branch conduit 4. Mixer 8 is conventional and comprises a cylindrical housing having fixed pins extending radially inwardly from the wall. A stirrer is provided with pins which extend outwardly and may move between the pins affixed to the walls of the cylindrical housing.

The apparatus described above serves to meter a viscous stream to a fiber spinning machine.

Gear pump 2 is designed for a delivery rate of 10,000 liters/hour and pump 5 for a rate of 500 liters/hour. Pump 6 is designed for a rate of 630 liters/hour. Only a fraction of these quantities, however, passes through the gear pump 13, namely 5 liters/hour, and serves to lubricate the pump 6.

Through the supply conduit 7 titanium dioxide is fed to the system at a rate of 125 liters/hour.

In FIGURE 2 the gear pump 6 is shown in detail. The pump comprises part 15 in which drive shaft 21 is mounted. Against part 15 there is mounted a pack of flat plates 16, 17, 18, 19, and 20. These plates are provided with openings serving to channel the liquid (not shown) to be pumped and to receive and house the gears and the shafts.

Drive shaft 21 is rotated in the direction indicated by the arrow. On this shaft there is a gland 22 which is pressed against a packing system 23 and insures that a liquid-tight seal is obtained between the driving shaft and the pump.

A rotor shaft 25 connects to shaft 21 and is driven thereby via a coupling member 24. Rotor shaft 26 is driven by the intermeshing of gears 27 and 28. All shafts inside the pump are provided with helical grooves 29, and with oppositely directed helical grooves 30. Such grooves serve to aid in the pumping of the liquid being introduced to gears 27 and 28. Liquid is supplied to the bearings and grooved shaft through the system of channels 31 to 36. Channel 12 (shown in FIGURE 1) connects to inlet opening 31.

The gear pump 13 serves to pump a minor proportion of unmixed viscose through conduit 12 into the inlet opening 31. From this point this stream of viscose flows through channels 32 to 36, passing through the grooves 29 and 30 reaching the side faces of the gears 27 and 28. The viscose then flows radially outwards along said faces and around the circumferential surfaces of the gears 27 and 28 where it is mixed with the previously admixed viscose. Thus, viscose supplied by line 4 and containing an abrasive component will be prevented from penetrating between the side faces of gears 27 and 28, and plates 17 and 19. Accordingly, wear of said side faces and plates and of the shafts 26 and 25 is prevented.

Other variations and modifications of the present invention will be apparent to those skilled in the art, and it will be understood that it is intended that the scope of the present invention be limited only by the scope of the appended claims.

What is claimed is:

1. A method of preventing wear in metering pump moving parts used to supply an abrasive additive to a viscous liquid solution comprising injecting to said pump a separate and distinct unmixed portion of said viscous liquid to wash and lubricate said moving parts thereof and at a pressure sufficient to prevent contact of the abrasive additive with said parts.
- 55 2. A method as defined in claim 1 wherein said viscous liquid is a liquid used to form filaments, fibers, and film.
3. A method as defined in claim 1 and comprising providing said viscous liquid with an abrasive additive in a primary bypass stream leading from a main stream of viscous liquid flow.
- 60 4. An apparatus for admixing a pigment suspension with a spinning liquid, comprising a main spinning liquid conduit provided with a pump, a primary bypass conduit connected to the main conduit in which two gear pumps are located and separated by an inlet for the pigment suspension, and a second bypass conduit connected to said main conduit, said second bypass conduit also provided with a gear pump for independently feeding a portion
- 65 70 75 of the unmixed spinning fluid to serve as a lubricating

liquid to the last gear pump located in the first bypass conduit.

5. Apparatus according to claim 4 wherein said last gear pump is provided with a feed inlet communicating with a system of channels, said system adapted for feeding an unmixed spinning liquid to a drive shaft and rotor shafts within said pump, said shafts further having means to feed said liquid to side faces of gear mechanisms attached to and driven by at least one of said rotor shafts.
